UNITED STATES PATENT OFFICE

100,292

DESIGN FOR A VELOCIPED

Mayo E. Roe, Elyria, and Wilbur Henry Adams,
Cleveland, Ohio, assignors to The Colson Cor-
poration, Elyria, Ohio, a corporation of Ohio

Application May 11, 1936, Serial No. 62,597

Term of patent 7 years

To all whom it may concern:

Be it known that we, Mayo E. Roe and Wilbur Henry Adams, both citizens of the United States, residing at Elyria, in the county of Lorain and State of Ohio, and at Cleveland, in the county of Cuyahoga and State of Ohio, respectively, have invented a new, original, and ornamental Design for Velocipedes, of which the following is a specification, reference being had to the accompanying drawing, forming a part thereof, in which:

Fig. 1 is a perspective view of a velocipede showing our new design.

Fig. 2 is a detail plan view of the frame member shown in full lines in Fig. 1.

The dominant feature of our design resides in the portion shown in full lines in each of the figures.

We claim:

The ornamental design for a velocipede, substantially as shown and described.

In testimony whereof, we hereunto affix our signatures this 29th day of April, A. D. 1936, and this 28th day of April, 1936, respectively.

MAYO E. ROE.
WILBUR HENRY ADAMS.
